UNITED STATES PATENT OFFICE.

DUDLEY H. ROBEY, OF INDIANAPOLIS, INDIANA.

VALVE MECHANISM FOR INTERNAL-COMBUSTION ENGINES.

Specification of Letters Patent. Patented Apr. 18, 1916.

1,179,655.

Application filed April 4, 1914. Serial No. 829,561.

To all whom it may concern:
Be it known that I, DUDLEY H. ROBEY, a citizen of the United States, and a resident of Indianapolis, county of Marion, and State of Indiana, have invented a certain new and useful Valve Mechanism for Internal-Combustion Engines; and I do hereby declare that the following is a full, clear, and exact description thereof, reference being had to the accompanying drawings, in which like letters refer to like parts.

The chief feature of this invention is a cylindrical rotary valve with one or more flat bearing surfaces for engaging a flat seat or seats and the arrangement of the means for operating the valve, such as a worm screw and worm wheel, so that the same tends to hold the valve against its seat or seats. This means, therefore, automatically holds the valve to its seat and with uniformity at all times regardless of wear and the valve never wedges nor sticks so as to interfere with the rotation thereof.

Another feature of the invention is the arrangement of the intake and exhaust ports of the valve in the valve casing so that by cooperating with the port in the valve, it will cause but an extremely slight intermission between the exhaust and intake. There is only a slight movement of the valve, say six degrees, between the position when the exhaust is cut off and until the intake of fuel begins.

The full nature of the invention will be understood from the accompanying drawings and the following description and claims.

In the drawings, Figure 1 is a longitudinal vertical section through an internal combustion engine centrally of the cylinders, with parts partially broken away. Fig. 2 is a horizontal section on the line 2-2 of Fig. 1. Fig. 3 is a similar section on the line 3-3 of Fig. 1. Fig. 4 is a vertical transverse section on the line 4-4 of Fig. 3. Fig. 5 is a transverse section through a modified form of the valve casing and valve. Fig. 6 is a vertical section on the line 6-6 of Fig. 5.

In detail there is shown a series of cylinders 10 surrounded by suitable water chambers 11 and having top plates 13 and 14 through which a pair of intake ports 15 are provided, as shown in Figs. 1 and 3. Upon the series of cylinders there is a frame secured consisting of a bottom plate 16, a top

plate 17, end plates 18 and side plates 19. This frame is provided with suitable cooling chambers, as shown in Fig. 2. In this latter frame there are a number of valve casings 20, one for each cylinder and in communication with the ports 15 of the cylinders. Each valve casing 20, as seen in Fig. 2, has an intake port 21 leading from the intake chamber 22, and an exhaust port 23 leading to the exhaust chamber 24.

Within each valve casing there is a cylindrical valve 25 with an upwardly extending stem 26 having a worm wheel 27 thereon which meshes with a worm 28 on a shaft 29 in a casing 30 resting upon the valve frame, as shown in Fig. 1. The shaft 29 is driven by a worm 31 thereon meshing with a worm wheel 32 on a vertical shaft 33 which has near its lower end a worm wheel 34 meshing with a worm 35 on a crank shaft 36 in a bearing 37. The crank shaft is driven by piston rods 38 connected with pistons 39 operating in said cylinders.

The valve 25 is cylindrical and has an outwardly extending horizontal flange 135 on its lower end operating beneath a shoulder or seat 136 in the valve casing 20. There is also a seat 137 at the upper end of the valve casing against which the upper end of the valve seats. The shaft 29 operates in the direction indicated by the arrow so that it tends to lift the valve 25 and hold it against the two seats 136 and 137 of the valve casing. The surfaces of the valve which engage said seats are horizontal and flat so that there is no wedging whatever of the valve in the seat and no tendency to stick or refuse to operate because of excessive friction.

In the seat of the valve there is a port 40 having a width slightly less but nearly as great as the shorter distance between the exhaust port 23 and the intake port 21 of the valve casing 20. For that reason the intake port is open almost immediately after the exhaust port has been closed and hence no time is wasted for the introduction of fuel into the cylinder. Within the valve there is a shield 45 which is open at the bottom and extends up beyond the port 40 so as to limit a passageway 46 and leave it with only an opening in the lower end thereof in position to register successively with the ports 15 in the top of the cylinder. When the chamber 46 registers with the first port 15, it establishes communica-

tion directly between the cylinder of the engine and the exhaust chamber 24 and when the chamber 46 registers with the other port 15, it establishes communication between the intake port 21 and the cylinder. In either event there is direct inlet for the fuel gas and outlet for the exhaust gas.

In the modified form shown in Figs. 5 and 6 there is packing between the valve 10 casing and valve consisting of vertical strips 40 in recesses in the inner wall of the valve casing, and bushings 41 in said recesses for forcing said strips inward against the valve.

15 The invention claimed is:

1. An internal combustion engine having a cylinder with a flat end with intake and exhaust ports therein, a cylindrical valve casing mounted thereon with an annular 20 recessed seat on the end adjacent the cylinder and an annular seat in the outer end thereof and intake and exhaust ports in the side thereof, an intake chamber in communication with the intake port in said casing, an exhaust chamber in communication with the exhaust port in said casing, a cylindrical valve in said casing with its inner end provided with an annular flanged seat adapted to fit in the recessed seat in the casing and with its outer end bearing against the outer seat of the casing, and 25 having a port adapted to register as the

valve is rotated with the ports in the side of the valve casing, and means for rotating said valve, which at the same time tends to hold it against said seats and prevent leakage.

2. An internal combustion engine having a cylinder with a flat end with intake and exhaust ports therein, a cylindrical valve 40 casing mounted thereon with an annular recessed seat on the end adjacent the cylinder and an annular seat in the outer end thereof and intake and exhaust ports in the side thereof, an intake chamber in communication with the intake port in said casing, an exhaust chamber in communication with the exhaust port in said casing, a cylindrical valve in said casing with a passageway leading from the end of said valve adjacent the cylinder to the side of the valve and adapted to register with the ports in the side of the casing, and means for opening said valve which at the same time tends to hold it against said seats and prevent leakage.

In witness whereof I have hereunto affixed my signature in the presence of the witnesses herein named:

DUDLEY H. ROBEY.
